UNITED STATES PATENT OFFICE

CHAUNCEY MARSH GOODRICH, OF WINDSOR, ONTARIO, CANADA

TRANSMISSION TOWER ARMS

Application filed March 16, 1929. Serial No. 347,576.

This invention relates to transmission towers and more particularly to the arm construction and mounting for such towers, and has for one of its objects the provision of a hinged arm construction adapted to be movable in the direction of the line.

Another object is to provide a hinged arm construction which will be yieldably held in position at right angles to the line.

10 In the drawings:—

Figure 1 is an elevation of a tower constructed in accordance with this invention.

Figure 2 is a sectional view taken through the tower arm on the line II—II of Figure 1.

15 Figure 3 is a sectional plan taken on the line III—III of Figure 1.

Figure 4 is an enlarged plan of the tower.

20 Figure 5 is an enlarged fragmentary detail showing the hinge mounting for the arm beams.

Figure 6 is a sectional view taken on the line VI—VI of Figure 5.

25 Referring more particularly to the drawings the numeral 2 designates the legs of the tower which are connected in the usual manner by horizontal and diagonal bracing members 3.

30 A triangular truss member 4 is formed above the main body of the tower by angle members 5 which are extended upwardly from the upper ends of the tower legs 2 and are connected at their upper ends by an angle bar 5^a.

35 The upper ends of the legs 2 of the tower are connected by horizontal angle members 6 and 7 forming a rim. The side members 6, which extend parallel to the line, serve as supports for the arm beams to be described and are connected to each other at a point intermediate their ends by a stiffening angle 8. The members 7 which extend at right angles to the members 6 and to the line are also connected by bars 9 which serve to further stiffen the upper end of the tower.

40 45 A pair of horizontal plates 10 are secured to each of the angle members 6 and are spaced apart by a spacing block 12. Arm beams 13, preferably, although not necessarily, composed of wood, are hingedly supported by the plates 10 by being provided with tongue

plates 14 which are mounted between the plates 10 and held in place by pivot pins or bolts 15.

50 Suitable attachment plates 16 are secured to the upper end of the truss member 4 and extend in a direction transverse of the line. Flexible truss bars 17 are connected to each end of the plates 16 and extend outwardly and downwardly to a point intermediate the ends of the respective arm beams 13 and have their 55 outer ends connected to attachment plates 18 secured to the beams 13.

55 A plurality of insulator hangers 19 are mounted on the arm beams 13 and the transmission line cables are secured thereto.

60 In operation, the arm beams 13 are normally held against swinging movement by the truss bars 17 so as to facilitate stringing of the cables. If an undue load is applied to one side of the arm beams 13, such as is 65 occasioned by the breaking of one of the cables, the arm beams 13 will swing with the load about their pivotal connection 15 and the truss bars 17 will flex to permit such swing. The truss bar 17 on the side of the 70 arm nearest the pull will flex and buckle while the other bar 17 will be in tension and remain as a support for the beam 13. The arched bar 17 will have a component in the 75 direction of the applied pull and will, therefore, have a tendency to return to normal position so as to assist in returning the beam 13 to normal position.

80 85 It will be understood that when one of the transmission line cables breaks the arm beams 13 will swing only a short distance, due to the fact that the unbroken cables and the resistance of the truss bars 17 serve to counteract the pull of the broken cable.

90 While I have shown and described only one specific embodiment of my invention it will be understood that I do not wish to be limited thereto, since various modifications may be made without departing from the scope thereof, as defined in the appended 95 claims.

I claim:

1. In a transmission tower, a transmission line supporting arm structure comprising 190 a pair of horizontally disposed vertically

spaced bracket plates secured to said tower at a point appreciably below the upper end thereof, a beam, a tongue rigidly secured to one end of said beam and projecting into the space between said bracket plates, a vertically disposed pivot pin passing through said plates and said tongue to form a pivotal mounting for said beam to permit horizontal swinging movement thereof, a pair of truss bars rigidly connected at transversely spaced points to the upper end of said tower and to the opposite sides of said beam, said truss bars being adapted to normally hold said beam against horizontal swinging movement about said pivot pin under normal loads, and being yieldable to permit swinging of said beam about said pivot pin under abnormal loads.

2. In a transmission tower, transmission line supporting arms extending outwardly from opposite sides thereof in a direction transverse to the line, each of said arms comprising a pair of horizontally disposed vertically spaced bracket plates secured to said tower at a point appreciably below the upper end of said tower, a beam, a tongue rigidly secured to one end of said beam and projecting into the space between said bracket plates, a vertically disposed pivot pin passing through said plates and said tongue forming a pivotal mounting for said beam to permit horizontal swinging movement thereof, a pair of truss bars rigidly connected at transversely spaced points to said tower at points appreciably above said bracket plates and to the opposite sides of said beam, said truss bars being adapted to normally hold said beam against horizontal swinging movement about said pivot pin under normal loads, and being yieldable to permit swinging of said beam under abnormal loads.

In testimony whereof, I have hereunto set my hand.

CHAUNCEY MARSH GOODRICH.
